Primary Examiner — Kevin K Rudzinski*Assistant Examiner* — Richard E Yenchesky(74) *Attorney, Agent, or Firm* — James L. Young; Westman, Champlin & Koehler P.A.(57) **CLAIM**

The ornamental design for a container liner as shown and described.

DESCRIPTION

FIG. 1 is a perspective view of a container liner;
FIG. 2 is a right side view of the liner of FIG. 1;
FIG. 3 is a left side view of the liner of FIG. 1;
FIG. 4 is a back view of the liner of FIG. 1;
FIG. 5 is a front view of the liner of FIG. 1;
FIG. 6 is a top view of the liner of FIG. 1; and,
FIG. 7 is a bottom view of the liner of FIG. 1.
The dashed lines in the figures show portions of the container and form no part of the claimed design.
